US00D709462S

(12) **United States Design Patent**
Arioka et al.

(10) **Patent No.:** US D709,462 S
(45) **Date of Patent:** ** Jul. 22, 2014

(54) **CASE FOR VACUUM CIRCUIT BREAKER**

(71) Applicant: **Mitsubishi Electric Corporation**,
Tokyo (JP)

(72) Inventors: **Masahiro Arioka**, Chiyoda-Ku (JP);
Tomotaka Yano, Chiyoda-Ku (JP);
Kyoichi Otsuka, Chiyoda-Ku (JP);
Satoru Yoshida, Chiyoda-Ku (JP);
Taehyun Kim, Chiyoda-Ku (JP); **Koji Sano**, Chiyoda-Ku (JP); **Yuta Nakayama**, Chiyoda-Ku (JP)

(73) Assignee: **Mitsubishi Electric Corporation**,
Tokyo (JP)

(**) Term: **14 Years**

(21) Appl. No.: **29/432,742**

(22) Filed: **Sep. 20, 2012**

(30) **Foreign Application Priority Data**

(57) **CLAIM**

The ornamental design for a case for vacuum circuit breaker, as shown and described.

DESCRIPTION

FIG. 1 is a front, top and right side perspective view of a case for vacuum circuit breaker, showing our new design;
FIG. 2 is a front elevational view thereof;
FIG. 3 is a left side elevational view thereof;
FIG. 4 is a top plan view thereof;
FIG. 5 is a bottom plan view thereof; and,
FIG. 6 is a cross-sectional view thereof; taken along line 6-6 of FIG. 3.

1 Claim, 5 Drawing Sheets
